UNITED STATES PATENT OFFICE.

JOHN W. STAUFFER, OF ELLENSBURG, WASHINGTON.

GASOLENE-STRAINER.

1,199,628.

Specification of Letters Patent. Patented Sept. 26, 1916.

Application filed January 4, 1916. Serial No. 70,228.

To all whom it may concern:

Be it known that I, JOHN W. STAUFFER, a citizen of the United States, residing at Ellensburg, in the county of Kittitas and 5 State of Washington, have invented certain new and useful Improvements in Gasolene-Strainers; and I do hereby declare the following to be a full, clear, and exact description of the invention, such as will enable 10 others skilled in the art to which it appertains to make and use the same.

This invention relates to new and useful improvements in a gasolene strainer to be detachably secured to a hose of a gasolene 15 supply pump or other gasolene supplying source, and one of its objects is the provision of a device of this character, which shall be simple, durable and efficient and which may be manufactured and sold at a comparatively 20 low cost.

A further object of this invention is the provision of means of detachably connecting this device to a hose of any ordinary construction, and having a wire frame provided 25 with a cap to close the lower end of the frame so as to cause the gasolene flowing therein to have a tendency to back upwardly within the frame before passing outwardly therefrom and which causes sediment or 30 other foreign matter to accumulate and settle to the bottom of the frame and accumulate within the cap.

A still further object of this invention, is the provision of a sack or bag constructed 35 of chamois or other suitable material, to be placed over the wire frame and detachably secured thereto, for collecting water and other foreign matter which may pass out through the wire frame with the gasolene 40 and prevent it from passing into the tank of an automobile, or any other receptacle which is being filled.

With these and other objects in view, as 45 will become more apparent as the description proceeds, the invention consists in certain novel features of construction, combination and arrangement of parts as will be hereinafter more fully described and claimed.

50 For a complete understanding of my invention, reference is to be had to the following description and accompanying drawing, in which:—

55 Figure 1 is a side elevation of the strainer with all of its parts in proper relation, Fig.

2 is a side sectional view, illustrating the various parts in an assembled position, and Fig. 3 is an enlarged detail sectional view taken through the wire frame.

Referring in detail to the drawing, 1 designates a hollow cylindrical pipe, having secured within the upper end a hollow cylindrical sleeve 2, having an angular flange 3 formed on the upper end thereof. An internally screw-threaded coupling 4, having 60 an inwardly directed flange 5, is slidably secured on the sleeves 2, to receive an externally screw-threaded plug, of a hose (not shown).

Secured to the pipe 1 at a point intermediate its ends by solder or other suitable fastening means 6, is a wire frame 5'. The wire frame 5' is of larger dimension than the pipe 1 to provide a space 7 to accommodate gasolene which will back upwardly 75 within the frame for a purpose which will be hereinafter more fully described. A cap 8, having an angular flange 9, is secured to the lower end of the frame 5' by solder or other suitable means to close the end of the 80 frame 5' and prevent gasolene from passing outwardly therefrom, which causes the gasolene to back upwardly within the wire frame 5' and dirt and other foreign matter will accumulate therein and settle within 85 the cap 8. A sack or bag 10 constructed of chamois or any other suitable material, is provided with loops 11 cut out in circular formation adjacent the open end to receive a string 12 for closing the open end when 90 desired. The bag 10 is pulled over the wire frame and the open end thereof is secured tightly upon the sleeve 2 by means of the string 12 forming a cover to the entire length of the wire frame 5' and which will 95 prevent water and other foreign matter from passing into a tank of an automobile or any receptacle which is being filled from a gasolene source. After the bag 10 has been in use on the wire frame 5' for a considerable time it may be readily removed by 100 untying the string 12, whereby all accumulation of foreign matter may be washed from the interior of the bag 10, the cap 8 and the accumulation on the wire frame 5'.

In operation the coupling 4 is secured to the end of a hose, carried by a gasolene pump and the gasolene therefrom will be conducted part way down the wire frame 5' 105 by the pipe 1 and cause to strike against the 110

cap 8 and back upwardly within the wire frame 5' and the bag 10 and pass outwardly through said bag 10 in a cleaned condition.

While I have shown and described the 5 preferred embodiment of my invention, it will be understood that minor changes in construction, combination and arrangement of parts may be made without departing from the spirit and scope of the invention as 10 claimed.

Having thus described my invention, what I claim is:—

1. A gasolene strainer comprising a hollow cylindrical pipe, a hollow cylindrical sleeve secured within the upper end of said pipe and provided with an outwardly directed flange thereon, a coupling provided with internal screw-threads and an inwardly directed flange on the lower end 15 adapted to slide upon said sleeve to be detachably secured to a hose, a wire frame secured to said pipe, a cap secured to the lower end of said frame for preventing liquid from passing therethrough and to 20 collect foreign matter, and means for incasing the wire frame to prevent foreign matter from passing outwardly with the gasolene.
2. A gasolene strainer comprising a hollow cylindrical pipe, a hollow cylindrical sleeve secured within the upper end of said 25

pipe, means carried by said sleeve for detachably connecting the sleeve to a hose, a cylindrical wire frame secured intermediate the ends of said pipe and of larger dimension than said pipe to provide a space therebetween, a cap secured to the lower end of said frame, a chamois bag positioned upon said frame and detachably secured to said sleeve for straining liquid passing outwardly from the lower end of said pipe.

3. A gasolene strainer comprising a hollow cylindrical pipe, a hollow cylindrical sleeve secured within the upper end of said pipe, means carried by said sleeve for detachably securing it to a hose, a cylindrical wire frame secured to said pipe intermediate its length and spaced therefrom, a cap secured to the lower end of said frame for causing liquid to back upwardly within the frame to collect foreign matter, and a chamois bag positioned upon said frame and detachably secured to said sleeve for entirely covering the frame and preventing foreign matter from passing outwardly therefrom, with the liquid.

In testimony whereof I affix my signature in presence of two witnesses.

JOHN W. STAUFFER.
